PLOW SHARE

Torsten August Andersson, Overum, Sweden, assignor to
Aktiebolaget Overums Bruk

Filed May 22, 1974, Ser. No. 472,104

Claims priority, application Sweden Nov. 28, 1973

Term of patent 14 years

Int. Cl. D15—03, 04

U.S. Cl. D35—2 A

FIG. 1

FIG. 2

FIG. 1 is a front perspective view of a plow share embodying my new design; and

FIG. 2 is a rear perspective view of the plow share shown in FIG. 1.

I claim:

The ornamental design for a plow share, as shown and described.
